UNITED STATES PATENT OFFICE.

BENNETT G. JANSSON, OF SAUGUS, MASSACHUSETTS, ASSIGNOR TO C. CHANDLER
BLAKE, OF BROOKLINE, MASSACHUSETTS.

METHOD OF MAKING INSULATED FASTENINGS.

Original application filed January 23, 1917, Serial No. 144,034. Divided and this application filed November 6, 1920. Serial No. 422,281.

To all whom it may concern:

Be it known that I, BENNETT G. JANSSON, a citizen of the United States, residing at Saugus, in the county of Essex and State of Massachusetts, have invented a new and useful Improvement in a Method of Making Insulated Fastenings, of which the following is a specification.

The present invention relates to fastenings which are used in telephone construction to secure telephone wires to woodwork, and is a division from my co-pending application Ser. No. 144,034, filed January 23, 1917, which has matured into Letters Patent No. 1,366,661, dated January 25, 1921.

These telephone wires are usually secured to the woodwork either by an insulated staple which straddles the wires or by a nail having a shank which passes between the wires. The staple carries a saddle of fibre which protects the insulating covers on the wires from the corrosive action of the metal of the staple. The nail, which has a wider range of utility than the staple, does not afford the insulating properties of the staple as the shank of the nail in being driven between the wires often cuts through the cover of the wires and forms a connection therebetween. Moreover, it is easy to knock the head of the nail from the shank during the wire-securing operation with the result that the sharp prongs for holding the head to the nail are exposed as a menace to the hands or clothing.

The object of the present invention is to produce a nail for securing telephone wires to woodwork which will be simple and cheap to manufacture, which will afford reliable insulation to the wires secured thereby, and which will permit the driving of the nail into hard woods without danger of the head becoming separated from the body portion of the nail.

To the accomplishment of these objects, and such others as may hereinafter appear, the various features of the present invention relate to certain methods of manufacture fully set forth hereinafter, the advantages of which will be readily understood by those skilled in the art.

The various features of the present invention will be readily understood from an in-

spection of the accompanying drawings illustrating the best form of the invention at present devised, in which,

55

Figure 1 is a longitudinal section of the die for producing the improved fastening with a strip of fabric for the cap positioned for the operation of the dinker;

Fig. 2 shows the cap dinked out of the strip and the nail with the cleat assembled thereon positioned for the operation of the plunger;

Fig. 3 shows the plunger partially elevated with the cap molded over the head of the cleat;

Fig. 4 shows the plunger at the end of its stroke with the body of the cleat compressed upon the nail, with the head of the cleat compressed within the skirt of the cap, and with the wire-separating seat formed upon the bottom of the cleat;

Fig. 5 is a vertical section of the insulated fastening embodying the features of the present invention;

75

Fig. 6 is a vertical section of the present telephone wire-fastening nail; and

Fig. 7 is a detail of the nail shown in Fig. 6 with the head thereof removed.

The present commercial nail for securing telephone wires to woodwork comprises a nail 1 (Figs. 6 and 7) the shank of which carries a metal strip 2 having a pair of prongs 3 formed thereon. These prongs are forced into a button 4 molded from paper pulp. In driving this nail into woodwork in order to secure a pair of telephone wires 5, the point of the shank often cuts into the cover of the wires and forms a connection between the wires. Moreover, the strip 2 sometimes is driven through the cover and short-circuits the wires 5. In driving this nail into hard woods the hammer-blows separate the button 4 from the prongs 3 and these prongs are then free to injure the hands or clothing:

As the button 4 is molded from paper pulp it is necessary to paint the nail in order to render its appearance attractive. This painting operation is performed by tumbling the nails in a barrel containing paint. The shank of the nail is thus provided with a coat of paint which seriously interferes with the penetration of the shank into wood thus necessitating the

delivery of hard blows on the button 4 to drive the nail home. Moreover, the thick button 4 acts as a cushion on the head of the nail and thus absorbs a part of the hammer-blows intended for the nail head.

In the illustrated embodiment of the present invention the nail 6 (Fig. 5) is provided with a wooden cleat 7 which is provided with a tapered teat 8 to facilitate its passage between a pair of telephone wires 9 and with a concave shoulder 10 for engaging the wires. The cleat 7 is compressed upon the nail 6 and is bound in compressed condition on the nail by a binder or cap 11 which is molded over the head of the cleat. The cap is preferably molded from a disk of fibre and consequently no painting operation is necessary as the natural finish of the fibre imparts an attractive appearance to the nail.

With this construction there is no danger of the nail forming a connection between the telephone wires as the part of the nail adjacent the wires is wood. The nail may be severely pounded while being driven into hard woods as the cap 11 securely holds the cleat 7 on the nail 6. Furthermore, as the fibre disk is comparatively thin the blows delivered on the cap are transmitted without loss to the nail head.

In making the fastening, an ordinary nail 12 (Fig. 2) is driven through the center of a cylindrical block of wood 13 in such manner that the head of the nail is embedded in the upper surface of the block. Conveniently, the nail and block are assembled and then positioned on an arm 14 in a die 15 having a support 16 for a strip of fibre 17. The die is provided with a dinker 18 which dinks out a disk 19 (Fig. 2) from the sheet of fibre. A plunger 20 is then elevated to lift the assembled nail and block from the arm 14 and position it against the disk 19. Continued elevation of the plunger pushes the assembled disk, block and nail up through a restricted throat 21 in the dinker 18. During this movement of the plunger the disk 19 is provided with a circumferentially depending skirt molded over the head of the block 13 into the wood of which it slightly sinks (Fig. 3).

The throat of the dinker is closed by a chamber 22 having a button-shaped cavity 23 therein which cooperates with the flaring edges 24 of the throat 21 to form a die cavity. Continued elevation of the plunger forcibly pushes the nail, block and molded disk into this cavity whereupon the block is compressed upon the nail and molded within the depending skirt of the cap. At the same time the upper end of the plunger 20 forms the teat 8 and concave wire-engaging shoulder 10. After the insulated nail is formed in the manner illustrated in Fig. 4, the chamber 22 is elevated and thereafter an ejector

25 is raised within the plunger 20 to engage the point of the nail and eject it from the machine.

While the embodiment of the invention has been illustrated and described as a fastening for use in telephone construction, it will be apparent to those skilled in the art that the fastening has utility in other arts, such, for instance, as upholstery.

What is claimed as new is:

1. That improvement in the art of making insulated fastenings which consists in assembling a nail having a head thereon and an insulating body in such relation that the head is within the body and near the surface thereof farthest from the nail point, and enclosing said surface and nail head with a suitable covering.

2. That improvement in the art of making insulated fastenings which consists in assembling a cleat on a nail, and sinking a cap into the material of the cleat to bind the cleat to the nail, substantially as described.

3. That improvement in the art of making insulated fastenings which consists in assembling a cleat on a nail, molding a cap, and compressing the cleat on the nail and beneath the cap, substantially as described.

4. That improvement in the art of making insulated fastenings which consists in assembling a cleat on a nail, molding a cap with a circumferentially depending skirt, and compressing the body of the cleat upon the nail with the head of the cleat compressed within the skirt of the cap, substantially as described.

5. That improvement in the art of making insulated fastenings which consists in assembling a cleat on a nail, molding a cap with a circumferentially depending skirt, and simultaneously compressing the body of the cleat upon the nail with the head of the cleat compressed within the skirt of the cap and forming a teat upon the bottom of the cleat, substantially as described.

6. That improvement in the art of making insulated fastenings which consists in assembling a cleat on a nail and binding the assembled cleat on the nail.

7. That improvement in the art of making insulated fastenings which consists in assembling a cylindrical block on a nail, dinking a cap from a strip of material, forcing the assembled block and nail into a restricted throat on the dinker to provide the cap with a circumferentially depending skirt enclosing the head of the block, closing the throat of the dinker to form a die cavity, and forcing the assembled block and cap into the die cavity to compress the block upon the nail with the head of the block compressed within the skirt of the cap.

8. That improvement in the art of making insulated fastenings which consists in assem-

bling a cylindrical block on a nail, dinking a cap from a strip of material, forcing the assembled block and nail into a restricted throat on the dinker to provide the cap with 5 a circumferentially depending skirt enclosing the head of the block, closing the throat of the dinker to form a die cavity, forcing the assembled block and cap into the die cavity to compress the block upon the nail 10 with the head of the block compressed within the skirt of the cap, and forming a teat on the bottom of the cleat.

9. That improvement in the art of making insulated fastenings which consists in assembling 15 a cylindrical block on a nail, dinking a cap from a strip of material, forcing the assembled block and nail into a restricted throat on the dinker to provide the cap with a circumferentially depending skirt enclosing the head of the block, closing the throat of the dinker to form a die cavity, forcing the assembled block and cap into the die cavity to compress the block upon the nail with the head of the block compressed 20 within the skirt of the cap, and forming a teat on the bottom of the cleat, and opening the throat of the dinker and ejecting the finished fastening.

10. The method of making nails which 30 comprises passing a headed nail axially through a circular cleat and sinking its head flush with one surface of the cleat, applying a cover to said surface, and flanging the cover about the periphery of said cleat to bind the cleat to the nail.

11. The method of making nails which comprises assembling a headed nail and a generally disk-like body with the shank of the nail projecting from one face thereof 40 and the head of the nail embedded in the other face, and then applying a cover to the body in a manner to retain the nail in its assembled relation to the body when the nail is driven.

45 12. The method of making nails which comprises assembling a headed nail and a generally disk-like body with the shank of

the nail projecting from one face thereof and the head of the nail embedded in the other face, and then molding a circular cover 50 over the face of the body containing the nail head, said molding including inturning the margin of the cover below said face to secure the cover and hold the nail in position.

13. The method of making nails which 55 comprises assembling a headed nail and a generally disk-like body with the shank of the nail projecting from one face thereof and the head of the nail embedded in the other face, applying a circular cover to the 60 face of the body containing the nail head, then turning down the margin of said cover to form a skirt about the periphery of the body and finally inturning said skirt to secure the cover in position. 65

14. The method of making nails which includes the steps of manipulating a circular cleat and a wire nail in a manner to position the cleat on the shank just below the head of the nail, forming a projecting teat 70 from the material of the cleat about the shank of the nail, and covering the head of the nail with a disk of sheet material the margin of which extends to and is inturned about the peripheral edge of the cleat. 75

15. The method of making nails which includes the steps of driving a headed nail through a disk-like block, securing said nail in place by molding a cover over the end of said block opposite the nail point, and forming a central teat projecting from the other end of said block. 80

16. The method of making nails which comprises driving a headed nail through an annular cleat in such manner that the head 85 of the nail is flush with one face of the cleat, concealing the head of the nail by a cover of sheet material fitted over the cleat, and securing said cover in place by flanging its margin about the peripheral edge of said 90 cleat.

In testimony whereof I have signed my name to this specification.

BENNETT G. JANSSON.
